Primary Examiner—Robin V. Taylor

(74) Attorney, Agent, or Firm—Browning Bushman

(57) **CLAIM**

The ornamental design for a waste treatment plant, as shown and described.

DESCRIPTION

FIG. 1 is a perspective view of one embodiment of the waste treatment plant of the present invention;
 FIG. 2 is a top, plan view of the waste treatment plant of FIG. 1;
 FIG. 3 is a front, elevational view of the waste treatment plant of FIG. 1;
 FIG. 4 is a rear, elevational view of the waste treatment plant of FIG. 1;
 FIG. 5 is a bottom, plan view of the waste treatment plant of FIG. 1;
 FIG. 6 is a side, elevational view of the waste treatment plant of FIG. 1;
 FIG. 7 is an opposite side, elevational view of the waste treatment plant of FIG. 1;
 FIG. 8 is a top, plan view of another embodiment of the waste treatment plant of the present invention;
 FIG. 9 is a front, elevational view of the waste treatment plant of FIG. 8, the rear, elevational view being the same as the rear, elevational view of the waste treatment plant shown in FIG. 4 modified as shown in the front, elevational view of FIG. 9; and,
 FIG. 10 is a bottom, plan view of the waste treatment plant of FIG. 8.
